UNITED STATES PATENT OFFICE.

JAMES NOLAN ALEXANDER, OF PRATT CITY, ALABAMA, AND LYLE G. ATKINSON, OF MIAMI, FLORIDA.

REMOVING DEVICE.

Application filed September 5, 1925. Serial No. 54,765.

This invention relates to a removing device and has for its object to provide, in a manner as hereinafter set forth, a device of the class referred to, provided with means 5 for loosening and removing foreign substances, such as metallic or other particles that become lodged in the eyes.

Further objects of the invention are to provide, in a manner as hereinafter set forth, 10 a removing device for the purpose set forth, which is simple in its construction and arrangement, strong, durable, compact, thoroughly efficient and convenient in its use, and inexpensive to manufacture.

15 With the foregoing and other objects in view, the invention consists of the novel construction, combination and arrangement of parts, as hereinafter more specifically described and illustrated in the accompanying drawings, wherein is shown an embodiment 20 of the invention, but it is to be understood that changes, variations and modifications can be resorted to which come within the scope of the claim hereunto appended.

25 In the drawings wherein like reference characters denote corresponding parts throughout the several views:

Figure 1 is an elevation of a removing device, in accordance with this invention, with 30 the cap removed.

Figure 2 is an elevation of the device with the shifting element and clamping sleeve for the latter removed.

Figure 3 is a vertical sectional view of the 35 clamping sleeve.

Figure 4 is a top plan view of the device with the shifting element removed.

Figure 5 is a fragmentary view, in elevation, illustrating the protecting cap in 40 position.

A removing device, in accordance with this invention, comprises a particle shifting element, a particle removing element of the attraction type, clamping means for the 45 shifting element, a handle member, and a protecting cap. The removing element is formed of magnetized metallic material, preferably steel, to provide a magnet capable of loosening and removing foreign substances which become lodged in the eyes. The shifting element is formed from a flexible strand, preferably hair.

The handle member is indicated at 1 and 50 may be of any suitable construction, preferably as shown, and which has secured to

the outer end thereof, in any suitable manner, the removing element referred to generally by the reference character 2, formed from a length of magnetized metallic material and consisting of a base 3 having projecting therefrom four arms 4 of equal length and each of which is quadrant-shaped in cross-section. Each of the arms 4, in proximity to its outer end, is provided with peripheral threads 5, and the threads 5 of one arm are so disposed to provide a continuation of the threads 5 of an adjacent arm. The outer end of each of the arms 4 is rounded, as at 6, so that when the arms are secured in abutting engagement, through a means to be presently referred to, the outer end of the element 2 will be semi-spherical in contour. The arms 4, in connection with a clamping sleeve to be presently referred to, form a clamp for fixedly securing the shifting element in loop-like form. Normally the arms 4 are spaced from each other to provide passages 7 disposed at right angles with respect to each other, and two of said registering passages are adapted 70 to receive the shifting element when the latter is arranged in loop-like form, as shown in Figure 1.

The shifting element is indicated at 8 and is of a length whereby loops 9 of varying 75 lengths may be formed and extended from the end 6 of the element 2.

The removing element 8 is clamped between a pair of arms 4 by a sleeve 10 provided on its inner face with threads 11, 80 which terminate at a point removed from the upper end of said inner face. That portion of the inner face of the sleeve 10, which is not provided with the threads 11, is smooth and curved, as at 12, so as to snugly 85 fit the outer end of the element 2, and further to provide for a portion of the outer end of the element 2 to project therefrom, as shown in Figure 1. A protecting cap 13 is provided for the element 2 when the device is not used.

When using the device the cap 13 is removed and if it is not desired to shift the particle in the eye through the medium of the element 8, the said element is not connected with the element 2, but the latter is employed to attract and remove the particle from the eye. If it is desired to shift the particle which is lodged in the eye, so it can be positioned to be attracted and removed by 100 105 110

the element 2, the element 8 is connected to the element 2 in a loop-like manner, as shown in Figure 1, and the particle shifted, after which the element 8 is disconnected 5 from the element 2 and the latter can be employed to attract and remove the metallic particle. In some instances the element 8 can be employed to remove particles lodged in the eyes. The sleeve 10 engages with the 10 threads 5 of the arms 4.

It is thought that the many advantages of a removing device, in accordance with this invention, can be readily understood, and although the preferred embodiment of 15 the invention is as illustrated and described, yet it is to be understood that changes in the details of construction can be had which will fall within the scope of the invention as claimed.

20 What we claim is:—

A removing device for the purpose set

forth comprising a handle element, a length of magnetized metallic material including a base at its inner end secured to the outer end of said handle and further including a 25 lengthwise slotted portion projecting from the base, the outer end of said slotted portion being curved to provide a semi-spherical head, said length of material forming an attraction element provided with peripheral 30 screw threads intermediate its ends, an adjustable flexible shifting element of loop-like form extending within and projecting from the outer end and sides of said slotted portion, and means engaging with said threads 35 for clamping lengths of said shifting element within said slotted portion.

In testimony whereof, we affix our signatures hereto.

JAMES NOLAN ALEXANDER.
LYLE G. ATKINSON.
